UNITED STATES PATENT OFFICE.

SAMUEL E. TOMPKINS, OF SING SING, NEW YORK.

IMPROVEMENT IN HARNESS-SADDLE TREES.

Specification forming part of Letters Patent No. **152,192**, dated June 16, 1874; application filed
January 31, 1874.

To all whom it may concern:

Be it known that I, SAMUEL E. TOMPKINS, of Sing Sing, in the county of Westchester and State of New York, have invented a new and Improved Harness-Saddle Tree, of which the following is a specification:

This invention consists, essentially, of the terret-nuts fastened to the backband, in combination with the upper elevated and lower depressed bridges of the tree, instead of fastening them to the upper bridge or to the under bearing-plates, as they have heretofore been arranged, the objects being to enable the saddles to be made and kept in store ready for sale without fitting on the terret-mountings, to allow the purchaser to select the mountings to his taste, also to preserve the mountings better until sold by keeping them in their packages. These objects are effected by attaching the terret-nuts to the backband when they cannot be by any other present mode, because the nuts, being selected to fit the terret-screws wanted by the purchaser, the nuts suiting the screws can be readily fastened on the backband, and the latter can be put in the tree to receive the terrets, whereas in all other modes the terret-nuts cannot be satisfactorily attached after the saddle is made. It is necessary to select the nuts to fit the screws, because there are no standards of size to which manufacturers of these articles conform, so that when the nuts are built into the saddle, as heretofore, the mountings cannot be changed for want of being able to procure others that will fit the nuts. The invention also consists of an improved construction of the crupper-loop, whereby it can be removed at any time and another put in place without removing the filling or middle piece of leather usually placed between the seat and the frame where crupper-loop is attached.

Figure 1 is a longitudinal sectional elevation of a harness-saddle constructed according to my invention. Fig. 2 is a section on the line *x x* of Fig. 1. Fig. 3 is a section of Fig. 1 on the line *y y*. Fig. 4 is a plan of the back-strap and terret-nut as arranged in the left-hand side of Fig. 1. Fig. 5 is a longitudinal sectional elevation of the back-strap as arranged in the right side of Fig. 1. Fig. 6 is a plan of a metal connecting-piece for the back-strap with a terret-nut attached to it, showing how to adapt

it to my invention. Fig. 7 is a longitudinal sectional elevation of Fig. 6. Fig. 8 is a front elevation, and Fig. 9 is a cross-section, on line *v v*, of a tree whereof the upper bridge, upon which my present mode of attaching the terret-nuts mainly depends, is detachably connected to the tree. Fig. 10 is a plan of the under side of a portion of a saddle-tree, showing the form in which I now construct the lower bridge for the use of pad-screws for fastening the jockeys to the backband. Fig. 11 is a plan of the tree, together with the crupper-loop and middle leather, showing the manner of connecting the crupper-loop for taking it out without removing the middle leather. Fig. 12 is a plan of Fig. 11 without the middle leather. Fig. 13 is a section through Fig. 11, also the saddle on the line *w w*; and Fig. 14 is a plan of the crupper-loop. Fig. 15 is a plan view, and Fig. 16 a cross-section, of a modified arrangement of the plate used to secure the terret-nut to the backband. Fig. 17 is a plan view, and Figs. 18 and 19 are cross-sections, of another modification of said plate.

Similar letters of reference indicate corresponding parts.

A represents the side portions of a tree having a middle longitudinal channel, *B*, for the back-strap between the flanges *C*, with a bridge, *D*, passing over the channel where the terret-mountings are put on, and another, *E*, passing under the channel at the lower end of the tree. To a tree of this kind, or any similar character, I now propose to attach the terret-mountings and the back-straps independently of the under bearings which have heretofore been used for holding the nuts for the terret-screws, and sometimes for the pad-screws, by fastening the terret-nuts directly to the backband and screwing the latter up snugly against the bridge, and also attaching the pad-screw nut to the lower bridge *E*. *F*, *F'*, and *F''* represent the backband in different forms, to which the terret-nut *G* is connected, the connection being varied to suit the different requirements of the backband, or as may be preferred by the constructor.

In Fig. 4, and in the left-hand side of Fig. 1, the nut being fitted in a hole in the center of the backband, a re-enforcing-plate, *H*, of metal, is applied to the backband to strengthen it, said band being weakened by the hole for the

nut. Said plate is riveted on opposite sides of the hole by the rivets I, also by others, J, and also by the rivets K, which fasten the nut to the band. The rivets J are arranged relatively to the nut, so as to prevent it from being turned in the leather by the terret-screw in case it binds. The plate is also flanged at L to confine the band at the edges and prevent them from bulging, but it may be made without the flanges. Sometimes it might be best to secure the plates H to the backband before the nuts are attached. In such cases the plates will either be provided with ribs m or with a depression, n, Figs. 15 to 19, to prevent the nuts from being turned out of place by the terret-screws. The depression may be deep enough to sink the nut flush with the surface of the plate.

In some cases, as when such a strap as F¹, in the right hand of Fig. 1 and in Fig. 5, is used, the re-enforcing-plate may be dispensed with, and when a metal strap, F², Figs. 6 and 7, is used, it will be re-enforced with leather pieces M N on the under side to make sufficient thickness for the nut, and to fit snug. The lower sunken bridge will have a hole, 5, for the pad-screw nut when the backband is connected in this way, so that the tree will be adapted for a single-pad screw.

This invention is alike applicable to bridges cast together with the tree or made separate from it, and attached as in Figs. 8 and 9.

I now propose to fasten the crupper-loop by a screw, b, in combination with the steady-ing-boss e, said screw screwing into threads formed in a hole in the tree, and I also provide holes d, by which it may be riveted on, if preferred, or if the threads for the screws fail, as a means

of connecting it calculated to be more permanent than the modes heretofore used, and offering less obstruction to the removal of the loop and putting in others in case of need. For example, when a stud is cast on the tree to be used instead of the screw, the thread formed on it is not reliable, and it makes it necessary to remove the middle leather to get the loop off, and the nut put on being clumsy and objectionable, whereas in this case the threads, being formed in the trees, are more permanent, and in case they do fail resort may always be had to the rivet-holes d.

Having thus described my invention, I claim as new and desire to secure by Letters Patent—

1. The terret-nuts attached to the backband, in combination with the bridges and re-enforcing-plates, substantially as specified.
2. The re-enforcing-plate H, for strengthening the backband and securing the nut, substantially as described.
3. A jockey-tree, the lower bridge of which has a hole in the center for the pad-screw nut, substantially as described.
4. The crupper-loop secured by a screw screwing into the tree, in combination with the steady-ing-boss e, substantially as described.
5. The crupper-loop provided with the holes d for rivets in addition to the fastening-screw, substantially as described.
6. The removable crupper-loop secured directly to the tree by a screw, b, substantially as described.

SAM. E. TOMPKINS.
